DESIGN FOR A SIGN PANEL

Irene I. Melby, Alexandria, Va.

Application May 15, 1941, Serial No. 100,966

Term of patent 14 years

To all whom it may concern:

Be it known that I, Irene I. Melby, a citizen of the United States of America, residing at Alexandria, and State of Virginia, have invented a new, original, and ornamental Design for a Sign Panel, of which the following is a specification, reference being had to the accompanying drawing forming a part thereof, wherein the figure is a front elevational view of a sign panel, showing my new design.

The article is of no appreciable or substantial thickness.

I claim:

The ornamental design for a sign panel, as shown and described.

IRENE I. MELBY.
